UNITED STATES PATENT OFFICE.

ALBERT W. FRANKLIN, OF NEW YORK, N. Y.

DESIGN FOR A COMBINED PENDENT CIGAR AND CIGARETTE LIGHTER AND LAMP SWITCH.

Application filed June 23, 1928. Serial No. 27,242. Term of patent 3½ years.

To all whom it may concern:

Be it known that I, ALBERT W. FRANKLIN, a citizen of the United States, residing in New York, in the county of Bronx and State of New York, have invented a new, original, and ornamental Design for a Combined Pendant Cigar and Cigarette Lighter and Lamp Switch, of which the following is a specification, reference being had to the accompanying drawing, forming part thereof.

The figure is a side elevational view of an ornamental design for a combined pendent cigar and cigarette lighter and lamp switch. The various parts are in contrasting colors.

I claim:

The ornamental design for a combined pendent cigar and cigarette lighter and lamp switch substantially as shown and described.

In testimony whereof I have hereunto set my hand on this 18th day of June, A. D. 1928.

ALBERT W. FRANKLIN.
